UNITED STATES PATENT OFFICE.

JOHN KRAMER, OF WEST PERRY, SNYDER COUNTY, ASSIGNOR OF ONE HALF
TO JOSEPH LONG, OF MCALISTERVILLE, PENNSYLVANIA.

CAR-COUPING.

SPECIFICATION forming part of Letters Patent No. 366,779, dated July 19, 1887.

Application filed April 28, 1887. Serial No. 236,458. (No model.)

To all whom it may concern:

Be it known that I, JOHN KRAMER, a citizen of the United States, residing at West Perry township, in the county of Snyder and State of Pennsylvania, have invented certain new and useful Improvements in Car-Couplings; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to car couplers, and has for its object the production of novel means for automatically coupling and uncoupling the cars when run together, which will be more fully hereinafter set forth, claimed, and shown 20 in the annexed drawings, in which—

Figure 1 is a perspective view, parts broken away, of the approximate ends of two cars embodying my invention; Fig. 2, a vertical section of one part of the coupler, taken through 25 the throat of the draw-bar; Fig. 3, a view similar to Fig. 2 of the other part of the coupler.

The coupler is composed of two parts. One part is placed on the end of one car, and the other part is placed on the opposite end of the 30 car to be coupled thereto. The coupling-pin of one car is supported by holding devices in readiness to engage the link carried by the car to be coupled, and the other car (the one to be coupled) is provided with a trip-arm to release 35 the holding devices when the two cars are run together for coupling them.

The draw-bars are constructed alike, and are composed of a front plate, A, having a central opening, and wings a on each side of the opening, formed from the plate, the plates or bars a' , bolted at their forward ends to the rear of the plate A and united at their rear ends, and the plates a^2 , bolted or otherwise secured to the inner sides of the bars a' . The draw-bar C has 40 four standards or corner guideways, B, united thereto at their upper ends by the cross-bars B', formed with or separated from and secured to the standards, which are united at their lower ends by the short side bars, b, and the 45 transverse bolts b'. The pin-carrier, composed

of an upper and lower cross-head, D and D', respectively, and the corner posts D² uniting the plates, is guided in its movements by the lower cross-head working between the guideways B, and by the corner posts passing through openings in the cross bars B' and through openings in the lugs or cross-bars B², secured to the draw-bar. The ends of the corner posts are threaded and extend through the cross-heads, and nuts d , mounted on the threaded ends and 55 located on each side of the cross-heads, hold them adjustably in position. The pin E is supported by the upper cross-head of the carrier, and is adapted to pass through coincident openings in the plates a' and a^2 of the draw- 60 head. The carrier may be held down by gravity; but a spring is preferably interposed between it and the draw-bar, and is located between the lower cross-head and the under side of the draw-bar, and is mounted upon the 65 corner-post. There may be one spring for each corner-post, if desired. The pin-carrier is held elevated by the lever F, mounted upon the arm f, the holding-bar G, and the arm H, provided with the stop h, which is adapted to 70 enter the opening g in the bar G. The inner end of the lever curves and is adapted to bear upon the upper cross-head about centrally thereof.

The draw-bar C is provided with the shaft 80 I, journaled in bearings J, depending from each side thereof. One end of the shaft projects beyond the side of the car, and has the hand-lever I' keyed thereto, for working it in its bearings for moving the link-clamp, which is 85 composed of the cross-head K and depending arms k, united at their lower ends by the rod k', which is connected with the shaft I by the arm i, projected therefrom. The cross-head K is located within the throat of the draw-bar, 90 and is adapted to clamp the link between it and the lower side of the draw-bar. The arms k pass loosely through the lower side of the draw-bar, and have coil-springs k² mounted thereon for holding the cross-head K down. 95

In practice the link L is inserted in the draw-bar C, and is passed under the cross-head of the link-clamp, and is held in position by the coupling-pin l. The coupling-pin E of the draw-bar C, held up by the lever 100

F and the bar G, passes over the stop h. The cars are now run together and the trip M secured to the car or draw-bar C'. Striking the bar G disengages it from the stop h, and the pin 5 and carrier, being free, fall, and the pin E engages the link and couples the cars.

Having thus described my invention, what I claim, and desire to secure by Letters Patent, is—

- 10 1. The combination, with two cars and a link and a trip carried by one of the cars, of a coupling-pin carrier, the lever F, the holding-bar G, and the stop for holding-bar carried by the other car, substantially as described, and 15 for the purpose specified.
2. The combination, with the draw-bar and the guide-standards, of the coupling-pin carrier composed of the corner-posts and the upper and lower cross-heads uniting the posts, 20 substantially as set forth.
3. The combination, with the draw-bar and the cross-bars located above and below the draw-bar and secured thereto, and having apertures at each end, of the coupling-pin carrier composed of the corner-posts passed 25 through the apertures in the cross-bars, and the upper and lower cross-heads, substantially as described.
4. The combination of the draw-bar, the

four guideways secured at their upper ends to 30 the draw-bar and connected at their lower ends by means substantially as shown, and the coupling-pin carrier composed of corner-posts and the upper and lower cross-heads, the spring, the lever F and arm f, holding-bar G, 35 arm H, and stop h, substantially as set forth.

5. The combination, with the draw-bar and the link-clamp composed of the cross-head K, arms k, and the rod k' of the rock-shaft, means, as described, for imparting motion to the 40 shaft, and the arm connecting the rock-shaft and link-clamp, substantially as set forth.

6. The combination, with the draw-bar, the link-clamp, and the bearings depending from the draw-bar, of the rock-shaft journaled in 45 the bearings and having one end projected beyond the side of the car, the hand-lever secured to the projected end of the shaft, and the arm extended from the rock-shaft and connecting it with the link-clamp, substantially as set forth.

In testimony whereof I affix my signature in presence of two witnesses.

JOHN KRAMER.
